FIG. 3

Des. 195,560

PAGE 4

FIG. 5

FIG. 4

FIG. 6

FIGURE 1 is a perspective view of a telephone amplifier, showing my new design;
FIGURE 2 is a front elevational view thereof;
FIGURE 3 is a top plan view thereof;
FIGURE 4 is a left end elevational view thereof;
FIGURE 5 is a right end elevational view thereof; and

FIGURE 6 is a rear elevational view thereof.
I claim:

The ornamental design for a telephone amplifier, substantially as shown.
